UNITED STATES PATENT OFFICE

2,241,558

AIR-COOLED BOTTLED BEVERAGE COOLER

Roland S. Read, Bloomington, Ill.

Application September 9, 1938, Serial No. 229,043

1 Claim. (Cl. 62—102)

This invention relates to beverage coolers for bottled beverages of the dry or air-cooling type. Bottled beverages are dispensed in large quantities and the rapid cooling of such beverages presents the problem to which this invention is directed. It is generally recognized that the wet or immersion type of cooler is most effective for rapidly cooling bottled beverages but this method is objectionable on sanitary grounds. In fact, some States have legislated against the use of such coolers. Further, retailers object to the continual immersion of the hands in cold water.

Dry or air-coolers for bottled beverages have heretofore been slow to reduce the beverages to proper temperature and also have had wide variations in cooling performance between sections of the cooler.

The particular object of this invention is to provide a dry or air-cooling beverage cooler that is convenient and effective in operation.

Another object is to provide a cooler for bottled beverages that uniformly cools the bottles throughout the entire area of the cooler.

A still further object is to provide a cooler wherein the bottles may be cooled uniformly throughout the cooler whether they are stored horizontally or vertically or a combination of these two methods.

Other benefits and objects will be disclosed in the following descriptions and drawings in which:

Fig. 1 is a general perspective view of the cooler to show its general exterior appearance, location of door, etc.

Fig. 2 is a cross-sectional elevation view of the cooler as shown in Fig. 1, showing the general interior arrangement of cooling coils, air ducts, circulating fan, etc.

Fig. 3 is a sectional plan view of an optional arrangement of the cooling coils as they would appear from the section lines 3—3 of Fig. 4;

Fig. 4 is a sectional elevation view similar to Fig. 2 showing the optional arrangement of the cooling coils;

Fig. 5 is a cross-sectional elevation view similar to Fig. 2 showing another optional arrangement of the fan, cooling coils, air ducts, etc.;

Fig. 6 is a transverse or end elevation view of the optional arrangement of the coils, etc., as shown in Fig. 5, as they would appear on the section lines 6—6 of Fig. 5;

Fig. 7 is a sectional end elevation view similar to Fig. 6, but showing another arrangement of air ducts for cooling upright standing bottles; and

Fig. 8 is an exactly similar view of Fig. 7 showing the same arrangement of air ducts for cooling horizontally disposed bottles.

Now referring to Figs. 1 and 2, I designate the general exterior shell of the cabinet by the numeral 10. Mounted inside this cabinet is a shell 11 and interposed between the shell members is a conventional insulating material 12. Mounted within this insulation covering is a liner box 13 having a perforated bottom 14 and a conventional wire shelf 15. It will be noted that the bottom 14 has perforations 16 extending uniformly over the entire bottom area of the liner box. Supporting the insulating material under the bottom of the interior shell 11 from the side walls of the cabinet 10 is a solid shelf member 17.

A motor 18 is supported from the roof of the liner shell 13 by a bracket member 19 bridging the opening 20 in the liner shell. On the upwardly extending shaft of this motor 18 is a conventional centrifugal type blower fan 21. It will be readily appreciated that by the operation of this fan 21 air is drawn from the interior of the liner box and discharged through the top horizontal air duct 22. From there the air is driven through the cooling coils 23 and 24 in the vertical air ducts 25 and 25'. These vertical air ducts communicate with the lower horizontal air duct 26 and this air, cooled by the coils 23 and 24, is driven through the perforations 16 upward through the entire bottom area of the liner box and thence through the openings between the vertical standing bottles as illustrated. It will be appreciated that the perforations 16 in the bottom 14 are properly proportioned to the fan capacity so that the air is driven vertically through the liner box approximately uniformly throughout the entire area of the bottom 14.

A conventional compressor unit 27 is mounted in the bottom of the cabinet and is connected by tubing (not shown) to the cooling coils 23 and 24. Conventional hinged doors 29 and 29' are hinged to the cabinet shell 11, permitting communication to the contents of the liner box. Spring retained or snap type doors 30 and 30' are provided for communication with the compressor compartment. It will be noted that in a dry type cooler of the kind illustrated and described that multiple layers of bottles supported on shelving similar to 15 can be arranged and, therefore, the capacity of a dry cooler of this type greatly increased. This is of considerable advantage over wet coolers which ordinarily

only provide one layer of bottles in the tank with top door communication.

Now referring to Figs. 3 and 4, an optional arrangement of the cooling coil is illustrated. Instead of the cooling coils being disposed in the vertical air ducts 25 and 25', a circular or coil type cooling coil is disposed around the fan 21. It will readily be apparent that the air discharged from the fan 21 must pass over the cooling coil 31 as illustrated, and exactly similar results will be obtained as described for the arrangement shown in Fig. 2.

Now referring to Figs. 5 and 6 in which there is illustrated a still different optional arrangement of the cooler, the particular object of this arrangement is to provide means whereby the fan motor 38 is disposed exteriorly of the liner box in order to avoid the natural input of heat from the motor into the refrigerator compartment.

To accomplish this purpose the top of the liner box is completely removed and the bottom of the liner box enclosed in a tapered hood and fan housing 33. Communicating air passages 34 and 35 leading from the vertical air ducts 25 and 25' are provided by dropping the liner bottom 17' as illustrated. An air inlet 36 through the fan housing is provided to take the air from the ducts 34 and 35. The fan 37 is mounted on a shaft supported by bearings in the fan housing 33 and the motor 38 attached to this shaft is supported on the outside. The air from the fan 37 is driven over a large single cooling coil 32 and thence upwardly through perforations 16 of the bottom 14 exactly as heretofore described. By following the arrows indicating air flow, it is believed that this construction and operation will be clearly understood.

Now referring to Fig. 7, a variation of the construction shown in Figs. 5 and 6 is illustrated. In this construction the inside wall of the liner box is moved forward in order to provide a rear air duct 39. The top of the liner box is completely removed and the rear wall of the liner box is perforated by perforations 13'. The fan 37' has been rotated 90°, the shaft now running longitudinally in the cabinet and it will be understood that the motor (not shown) is mounted similarly to that shown in Fig. 6 exteriorly of the refrig-

erator compartment. A slanting air duct 40 communicates with the inlet to the fan housing 36' and provides a passageway for the air to be driven upwardly over the coil 32 exactly as described in Figs. 5 and 6.

Baffle plates 41 and 42 are hinged in the rear corners of the bottle compartments, as shown. When the bottles are stood on end, as shown in Fig. 7, these baffle plates are disposed vertically, thus forcing the flow of cold air over and around the standing bottles.

In Fig. 7 the bottles are shown disposed vertically and by following the arrows and appreciating that when bottles are stood together only a vertical passageway is provided for air, it will be understood that the air will be driven vertically through the openings between the bottles as well illustrated by the air flow arrows.

In Fig. 8 is illustrated the same arrangement of air ducts, fan, etc., but the bottles are disposed in a horizontal manner and the baffle plates 41 and 42 are in horizontal position. Now appreciating that when bottles so disposed greatly hinder the vertical passage of air, it will be appreciated that the air flow has been changed so that the major portion of the air passes horizontally over the bottles, such air flow being permitted by the perforations 13' in the rear wall of the liner box. It will therefore be understood that by this arrangement there is provided means whereby the cooling air flows over the bottles regardless of whether they are disposed vertically, horizontally or a combination of both methods, as with the bottles horizontal on the lower shelf and vertical in the upper.

Having thus described the invention, I now claim as new:

In an air-cooled bottled beverage cooler, a refrigerator cabinet, a liner box in said cabinet for supporting bottled beverages horizontally or vertically, cooling coils between the liner box and the cabinet walls, fan means for circulating air in heat exchange relationship to the cooling coils, air circulation perforations in the bottom and side walls of the liner box, and hinged baffle means for controlling the air flow through the liner box as required for properly cooling the bottled beverage stored horizontally or vertically.
